DESIGN FOR A FLASHLIGHT HEAD SHELL

William R. Westfall, Kew Gardens, N. Y., assignor to Scovill Manufacturing Company, New Haven,
Conn., a corporation of Connecticut

Application October 2, 1936, Serial No. 65,139

Term of patent 14 years

To all whom it may concern:

Be it known that I, William R. Westfall, a citizen of the United States of America, residing at Kew Gardens, Long Island, in the county of Queens and State of New York, have invented a new, original, and ornamental Design for Flashlight Head Shell, of which the following is a specification, reference being had to the accompanying drawing, forming a part thereof.

Fig. 1 is a side view of the flashlight head shell, embodying my new design.

Fig. 2 is a top plan view of the same.

Fig. 3 is a bottom plan view of the same.

The distinctive features of the present flashlight head shell resides in the ovoid shaped body terminating in a relatively narrow cylindrical skirt, and the intermediate portion of the body being ornamented with a plurality of equally spaced ovate-oblong convex decorative motifs, the degree of relief being in harmonious accord with the relative spacing of said motifs and the shape of the body.

I claim:

The ornamental design for a flashlight head shell substantially as shown and described.

WILLIAM R. WESTFALL.
